TOY BALL CATCHER

John H. Weimer, 445 High Meadow Road, Amherst, Ohio

Filed Nov. 25, 1964, Ser. No. 82,780

Term of patent 14 years

(Cl. D34—5)

I claim:

The ornamental design for a toy ball catcher, as shown and described.
